UNITED STATES PATENT OFFICE.

EDGAR H. CRANDALL, OF LOS ANGELES, CALIFORNIA.

GAME.

Application filed January 19, 1923. Serial No. 613,656.

To all whom it may concern:

Be it known that I, EDGAR H. CRANDALL, a citizen of the United States, residing at Los Angeles, in the county of Los Angeles 5 and State of California, have invented new and useful Improvements in Games, of which the following is a specification.

This invention relates to games and more particularly to the game of quoits, and has 10 for its object to provide an indoor apparatus for the game. Another object is to provide an indoor apparatus of substantial construction and which renders the game playable substantially noiselessly.

Another object is to provide means to 15 facilitate counting, and further to provide means for facilitating keeping score.

Other objects and advantages will be made manifest in the following specification 20 of an embodiment of the invention illustrated in the accompanying drawings, wherein—

Figure 1 is a perspective of the device as set for playing, and showing the quoit 25 ring in five point scoring position.

Fig. 2 is a vertical section transversely across the device omitting the quoit ring.

Fig. 3 is a perspective of the core body.

Fig. 4 is a perspective of the core case.

Fig. 5 is a perspective of the center pin.

Fig. 6 is a bottom plan of a quoit ring.

Fig. 7 is a top plan of the ring.

Fig. 8 is a section on line 8—8 of Fig. 7 on a larger scale.

The present apparatus consists of a core body constructed of material so as to provide a substantially noiseless cushion or bed so that when a quoit ring, such as is indicated at R, is thrown onto the apparatus, 40 the noise will not be of sufficient degree to be annoying. The pad, as shown, consists of an intermediate layer 2 of felt or fibrous loosely packed material of any suitable dimensions and here shown as of oblong form.

Top and bottom flexible protecting plates 3 cover the top and bottom faces of the core 2 and the piled elements have a central aperture 4. The body core thus described is preferably enclosed in a case 5 of flexible 45 material, preferably heavy canvas, the margins of which are stitched at 6 surrounding the core. The case 5 has also a central aperture 7 to register with the aperture 4 of the core body.

A center pin 8, having a substantial base

or flange 9, is adapted to be positioned in the center apertures of the pad structure and project up a sufficient distance to enable the ringing of the pin by the quoit ring R. The pin 8 is preferably jacketed by a flexible cushioning jacket or tube 8^a which, not only reduces noise during the play but, protects the parts against undue wear. The tube 9 may consist of a piece of rubber hose and is, therefore, of inexpensive construction and may be readily renewed when necessary.

To facilitate counting, an oblong or other suitably shaped target section 10, having a central aperture, is adapted to be placed over the top of the pad and centered and retained on or by the pin 8, and upon this target section there may be placed an inner and smaller target disc 11 centrally perforated to slip down over the pin 8.

Counting is facilitated, in the present apparatus, by giving a score of "1" to plays hitting the target section 10 and not being entirely on the center disc 11. Plays in which the ring rests partly on the target section 10 and partly on the disc 11 may be evaluated as "2"; plays in which the ring rests wholly on the disc 11 may be scored as "3" and those plays in which the ring touches but does not encircle the pin 8 are 85 scored as "4", while those plays in which the ring encircles the pin are counted as "5".

A form of quoit ring is clearly shown in Figs. 6, 7 and 8 in which the ring has a 90 flat annulus portion, the margins of which are beaded or rolled inwardly at R' thus forming overhanging shoulders beneath which may be inserted and retained removable and, therefore, renewable score keeping cards C consisting of segments of an annulus. These cards may be divided into concentric circles or arcs upon which may be registered the scores of the players and each card may be characterized by an index 95 means of any suitable character indicating ownership of the record kept on the face of the card sections.

This apparatus is not only adapted for use indoors, but is equally serviceable in the open, and the large target section 10 forms a protecting means when the apparatus is used on lawns, and it also serves as a shock absorbing element when the game is set up on hard surfaces, such as concrete 110

paving or floors in athletic halls and the like. The elongated target section also forms a landing for quoits which are underthrown or overthrown when played toward the disc.

The center pin 8 is preferably of metal to obtain a desired degree of stability for the apparatus.

The sheets or plates 3 forming a part of the core body may consist, for instance, of substantial oil cloth or linoleum.

It is understood that the bottom of the quoit may be smooth, or as is clearly shown, it may have a roughened, corrugated, or toothed lower face so as to tend to cling or be nonsliding when it strikes the target faces.

It is to be understood that instead of having a plurality of separate target sections any one, or a suitable number, may be employed.

Further embodiments, modifications and variations may be resorted to within the spirit of the invention as here claimed.

What is claimed is:

1. In quoit game apparatus, a quoit consisting of an annulus having detachable score keeping cards on one of its faces, and means for detachably retaining the score keeping cards in place.

2. In combination with a quoit ring, segmental cards, and means integral with the ring for securing the cards on the top face of the quoit ring.

3. In combination with a quoit ring, segmental cards, and means for securing the cards on the top face of the quoit ring, said means consisting of marginal inward-

ly turned beads beneath which the edges of the cards may be clinched.

4. In quoit game apparatus, a pad built of flexible, laminated sheets of cushioning material so as to eliminate, substantially noise of play produced by cast rings falling on the pad, the pad having a readily removable center pin.

5. In quoit game apparatus, a pad consisting of an inner core member of cushioning material, and an envelope enclosing the core and being of pliant material of the character to practically eliminate noise during play the pad being perforated from top to bottom, and a pin in said perforation.

6. In quoit game apparatus, a perforated pad consisting of an inner core member of cushioning material, a case enclosing the core and being of pliant material of the character to practically eliminate noise during play, and separate target forming top sections adapted to be removably laid upon the pad, and a pin insertable into the perforation of the pad.

7. In quoit game apparatus, a pad consisting of an inner core member of cushioning material, an envelope enclosing the core and being of pliant material of the character to practically eliminate noise during play, target forming top sections adapted to be laid upon the pad, and a centering pin passing through and maintaining position of the pad and the target forming top sections.

In testimony whereof I have signed my name to this specification.

EDGAR H. CRANDALL.
